UNITED STATES PATENT OFFICE.

HALE E. HAWK, OF GREENVILLE, MISSISSIPPI.

STEAMING APPARATUS.

1,118,856.

Specification of Letters Patent. Patented Nov. 24, 1914.

Application filed June 24, 1911. Serial No. 635,136.

To all whom it may concern:

Be it known that I, HALE E. HAWK, a citizen of the United States, residing at Greenville, in the county of Washington and State of Mississippi, have invented 5 new and useful Improvements in Steaming Apparatus, of which the following is a specification.

The invention relates to a steaming apparatus, and more particularly to the class 10 of combined crushers and steamers for crushing meats or kernels of cotton seed.

The primary object of the invention is the provision of an apparatus of this character 15 in which the meats or kernels of cotton seed, when introduced into the machine, will be thoroughly crushed and steamed, so as to soften the seeds or kernels while being crushed, thereby loosening the oils in the 20 cells thereof for its free extraction therefrom.

Another object of the invention is the provision of an apparatus of this character 25 in which the cotton seed kernels or meats will be properly moistened for the crushing thereof when passing through the crushing rolls of the apparatus, to enable the removal of the oil from the meats, and also in this manner, the meats will be purified and will 30 be given a brighter color, and likewise the oil when extracted.

A further object of the invention is the provision of an apparatus of this character 35 which is simple in construction, thoroughly reliable and efficient in operation, and inexpensive in manufacture.

With these and other objects in view, the invention consists in the construction, combination and arrangement of parts, as will 40 be hereinafter more fully described, illustrated in the accompanying drawings, and pointed out in the claims hereunto appended.

In the drawings: Figure 1 is a front elevation of an apparatus constructed in accordance with the invention. Fig. 2 is a 45 cordance with the invention. Fig. 2 is a vertical longitudinal sectional view therethrough. Fig. 3 is a sectional view on the line 3—3 of Fig. 1. Fig. 4 is a horizontal sectional view through one of the jet nozzles. Fig. 5 is an end elevation thereof, 50 looking toward its delivery end.

Similar reference characters indicate corresponding parts throughout the several views of the drawings.

Referring to the drawings by numerals, 55 the apparatus comprises as essential elements a frame or housing, a series of crushing rolls mounted in superposed relation therein, a series of cant boards, and a plurality of steam nozzles arranged so as to 60 supply steam between the lowermost crushing rolls of the series. The housing element includes spaced parallel sides 5 connected by bottom pieces 6, and by a top casing or hopper 7, wherein there is located a suitable 65 feeding device (not shown), operated in any preferred manner. The bottom pieces are shown as formed with inner sides 8 which are inclined toward each other and constitute, together with the adjacent portions of 70 the sides 5, a discharge hopper 9.

Journaled in the sides and transversely of the housing are crushing rolls 10, 11, 12, 13 and 14, the uppermost roll 10 being located directly beneath the hopper 7, while the 75 lowermost roll 14 projects into the discharge hopper 9. The several rolls are frictionally engaged, as is customary, the two live rolls 10 and 14 having their shafts or spindles 80 provided with driving pulleys, as usual, connected with a source of power.

Arranged within the frame, alternately at opposite sides of the crushing rolls, are diverting cant boards 15, the same being disposed so that their inner edges contact with 85 the outer surfaces of the crushing rolls, so that the meats or kernels of the cotton seed delivered from the hopper will be directed between and crushed by said rolls, at the points of nips thereof. During the several 90 crushing operations by the rolls 10, 11, 12, 13 and 14, the surfaces thereof are maintained in a clean state by reason of the contacting relation of the cant boards with respect thereto.

Located at one side of the roll 12, and at the reverse side of the roll 14, adjacent to the point of nips thereof with the roll 13, is a series of steam nozzles 16 which project 100 outwardly from supporting steam tubes or heads 17, each being connected with a branch supply pipe 18, which communicates with a

main supply pipe 19 leading from a steam boiler or other steam supply. Each nozzle 16 is outwardly tapered and is formed at one end with a flattened elongated discharge mouth 20, so that the steam emitted therefrom will be spread, fan-like, as it is discharged in the direction of the point of contact of each roll 12 and 14 with the roll 13. When the meats or kernels of cotton seed 10 are fed through the hopper 7 to the battery or gang of rolls, said meats or kernels will be crushed and ground, and the crushed mass, owing to the presence of oil and gummy substances will form substantially a 15 cohesive sheet which is guided by the cant boards so as to pass successively between the pairs of rolls from one side of the machine to the other and from the top to the bottom of the mill, being eventually discharged or 20 delivered into the hopper at the bottom of the casing. The steam nozzles, it will be observed, are arranged to project through the cant boards in the direction of the point of contact of some of the rolls, so that steam 25 will be discharged directly upon the underside of the sheet or mass of material passing through the mill. The action of the hot steam on the sheet or mass of crushed meats or kernels is to soften and loosen the mass, 30 to partly cook the same and also to sterilize the material. By the partial cooking the oil cells will be broken, and the subsequent extraction of oil greatly facilitated. By the loosening to which the material is subjected, 35 the crushing operation is rendered more effective; and the sterilization has a highly important effect on the value of the product, it having been found that meats which have become more or less musty and rancid are 40 restored to their original purity and flavor. The oil subsequently expressed from the product is found to be better and brighter in color and, therefore, of greater commercial value, and the oil cake resulting from 45 the subsequent pressing of the product is also found to be of vastly superior character to that resulting from the pressure of meal which has not been treated by the application of steam, as set forth.

50 As will be seen by reference to the drawings, the application of steam is made to the material as it passes between the two last pairs of rolls. It has in practice been found preferable not to apply steam during the 55 early stages of the crushing process, but the arrangement of the steam jets and the quantity of the steam discharged therethrough will be governed according to the dimensions of the mill, to the number of rolls employed, and in some degree according to the quality and condition of the material that is being operated upon. It will also be observed that owing to the construction of the nozzles, the steam will be discharged in fan-

like jets that will impinge directly on the 65 sheet or continuous cohesive mass of material that is passing through the mill, the steam being applied evenly to the entire under surface of the sheet or mass, being practically absorbed thereby, as has been demonstrated by practical tests of the invention. It is in no sense intended to deliver a spray or jet of steam on the surface of the rolls; 70 on the contrary, the spray or jet is directed to the material whereby the steam is absorbed. 75

Intersecting the steam supply pipe branches 18 are valve casings 21, in which are mounted manually controlled cut-off or regulating valves 22 which regulate the supply of steam to the steam nozzles 16. 80

What is claimed is:

1. In an apparatus of the class described, a series of superposed crushing rolls, a housing wherein said rolls are mounted, and cant 85 boards directed toward the points of contact of certain of said rolls, means for discharging steam transversely of the rolls in the direction of the points of contact of some of the crushing rolls, between the cant boards 90 and the material passing through the mill.

2. In an apparatus of the class described, a series of superposed crushing rolls, cant 95 boards coöperating with certain of the rolls to direct material toward the points of contact thereof, and means for discharging steam through the cant boards in a direction transversely of the rolls upon the material that is guided between the rolls.

3. A machine for crushing the meats and 100 kernels of seeds embodying a plurality of rolls whereby the material is successively subjected to a plurality of crushing operations, in combination with means for discharging steam toward and transversely of 105 the rolls directly upon the material that is being crushed prior to its passage between some of the rolls.

4. A machine for crushing the meats and 110 kernels of seeds comprising a plurality of rolls between which the material is successively guided and subjected to a crushing action, in combination with nozzles extending transversely of the rolls directed toward the points of contact of some of the rolls, said 115 nozzles being designed to produce fan-shaped blasts against the outer surface of the sheet of material, and means for supplying steam to said nozzles and for regulating the supply.

5. A machine for crushing the meats and 120 kernels of seeds, comprising a housing, a series of superposed crushing rolls journaled in said housing, cant boards within the housing, and directed toward the points of 125 contact of certain of said rolls, and series of nozzles extending through certain of said boards transversely of the rolls, said series

of nozzles being arranged on opposite sides of the series of rolls and so as to discharge fan-shaped blasts of steam toward the points of contact of certain of the rolls, so as to alternately subject the opposite sides of the sheet of material feeding through the rolls to steam heat pressure.

In testimony whereof I affix my signature in presence of two witnesses.

HALE E. HAWK.
